UNITED STATES PATENT OFFICE.

LAZARD KAHN AND ADAM SPECK, OF HAMILTON, OHIO, ASSIGNORS TO
F. & L. KAHN & BROS., OF SAME PLACE.

DESIGN FOR A STOVE.

SPECIFICATION forming part of Design No. 23,553, dated August 7, 1894.

Application filed June 2, 1894. Serial No. 513,321. Term of patent 7 years.

To all whom it may concern:

Be it known that we, LAZARD KAHN and ADAM SPECK, citizens of the United States, residing at Hamilton, Butler county, Ohio, have 5 invented and produced a new and original Design for Stoves, of which the following is a specification, reference being had to the accompanying drawing, showing a front view thereof.

Our stove design is characterized by the belt ring A, at the juncture between the combustion-section B and the fire-pot, which ring is a quarter circle in cross-section with its convexity upward, the convex surface being enriched by a continuous series of conventional 15 foliate ornaments each surmounted by an ornamental arch: by the roof-base F of substan-

tially quarter circle contour with convexity presenting and enriched by a continuous series of festoon-like ornaments: and by the 20 roof-piece G of convex form enriched by interlaced and pierced foliate scrolls: and by horizontal front panel E of rectangular form, enriched by foliate scrolls crossing at the center of the panel. 25

What we claim is—

The design for a stove substantially as shown and described.
